DESIGN FOR A CALENDAR

John Keith Clark, New York, N. Y.

Application July 31, 1942, Serial No. 107,775

Term of patent 3½ years

To all whom it may concern:

Be it known that I, John Keith Clark, a citizen of the United States of America, residing in the Borough of Manhattan, city of New York, county of New York, and State of New York, have invented a new, original, and ornamental Design for a Calendar, of which the following is a specification, reference being had to the accompanying drawing, forming part thereof.

Fig. 1 is a top plan view of a calendar showing my new design,

Fig. 2 is a side elevational view thereof,

Fig. 3 is a rear elevational view thereof.

I claim:

The ornamental design for a calendar, substantially as shown.

JOHN KEITH CLARK.
